UNITED STATES PATENT OFFICE.

GEORGE HENRY FOX, OF BOSTON, MASSACHUSETTS.

PISTON WATER-METER.

SPECIFICATION forming part of Letters Patent No. 327,671, dated October 6, 1885.

Application filed January 3, 1885. Serial No. 151,895. (No model.)

To all whom it may concern:

Be it known that I, GEORGE HENRY FOX, a citizen of the United States, residing at Boston, in the county of Suffolk and State of Massachusetts, have invented certain new and useful Improvements in Fluid - Meters; and I do hereby declare the following to be a full, clear, and exact description of the invention, such as will enable others skilled in the art to 5 which it appertains to make and use the same, reference being had to the accompanying drawings, and to letters or figures of reference marked thereon, which form a part of this 10 specification.

15 This invention relates to "fluid-meters," so called, and especially to that class in which a pair of pistons are employed and operated by cranks and connecting-rods so arranged with respect to each other as to overcome any tendency to a dead-center, and thereby prevent 20 stoppage.

25 My present invention may be considered as an improvement upon, and relates to, an application for Letters Patent on meters executed by myself on the 18th day of December, 1884.

30 The drawings accompanying this specification represent, in Figure 1, a vertical central longitudinal section of a meter embodying my improvements, while Figs. 2 and 3 show modifications of the same improvements.

35 Since this meter in general construction is similar to that shown in my previous application, I will describe it very briefly.

35 In these drawings, A represents the shell or outside casing of a meter provided with a cap, B.

40 Centrally of the shell and dividing it into two similar equal and corresponding chambers, C D, is the partition E, in which rotates a shaft, a, to which is attached the connecting-rods b c and cranks e f.

45 The valves are shown at F G as ordinary slide-valves, and co-operate with ducts g' h' h'', which alternately act as discharge and inlet passages, while common discharge - passages i i' lead to the general discharge or outlet orifice.

50 The water to be measured is introduced through the main inlet-port into the valve-chamber, and is thence conducted by means of the valves through the inlet-passages upon

either side of the two pistons, dependent upon circumstances and the position of parts at the time.

Attached to the upper part of the rotary shaft a is the registering-dial, so arranged and adjusted as to record each entire revolution of said shaft, which represents double the capacity of the two chambers C D.

Hitherto in meters of this class an almost insuperable objection has existed in overcoming the positive movement of the cranks and their connecting-rods with their operative pistons during the short interval or space of time 65 when the valve is changing its direction in movement or the reversal of its stroke. During that time both passages then acting as inlet and outlet ports are closed, and the liquid is held confined without any means of inlet or 70 exhaust. This position of the valve prevents the movement of the piston in this chamber, owing to the non-elasticity of water. Furthermore, during this interval of time the opposite piston and crank are traveling in unison with 75 the crank and connecting-rod attached to the piston in the measuring-chamber, which is closed by the valve, and thus all of the various parts connecting the two pistons are subjected to great strain, and some one of the parts is 80 liable to be so bent and twisted as to affect the efficiency of the machine, or else break and render the apparatus useless for the time, until repairs may be made.

The object of my invention is to overcome 85 the above serious objections now existing in meters of this class; and for this purpose I propose to loosely attach the pistons H I to their respective connecting-rods b c, whereby, when one piston is prevented from movement 90 by the position of the valve in reversing its motion, still the connecting - rod is perfectly free to advance to its extreme throw, which it usually attains just at that very moment. Thus in Fig. 1 I have constructed and cast 95 cylindrical projections j j upon the outside of the heads of the pistons of a diameter slightly larger than the hole through which the connecting-rods pass, in order to retain the piston in proper position thereon. Within said abutments are inserted disks k k', which are connected to the ends of said rods b c. Furthermore, the length of said chamber extends beyond the extreme point ever reached by the 100

disks $k k'$ upon the connecting-rods consequent upon the throw of the cranks $e f$. Screw-caps $l l'$, mounted upon the ends of said projections, close communication between opposite sides of the pistons.

In Figs. 2 and 3 I have shown slight modifications of methods whereby the piston may be loosely attached to the connecting-rods. In the former drawing I have constructed a central hub to form a bearing and afford suitable support to the connecting-rod, which is provided with a fixed shoulder, m , and adjustable nut n , the distance between the two forming a bearing longer than the journal-surface m' of the piston; hence the rod is free to advance without affecting the position of the piston, which remains stationary. In the latter figure I have represented a vertical pivot, at p , to which is attached the end of the connecting-rod. The latter is slotted at n' sufficiently to overcome the slight advance movement of said rod at the time the piston has stopped and the crank has attained its extreme throw, and thus obviate and overcome strains or thrusts which otherwise would occur.

The operation within the meter of my improvements is as follows: It being understood that piston I has just reached that position in which its valve G has closed both the passages $h h'$, prior to a change in its movement or reversal of the stroke; hence there is no communication from or into said chamber D, and the liquid, which is now upon both sides of the piston I, is confined. During this interval the crank f must still advance a short distance with its connecting-rod c in order to pass the center or the position of axial alignment of said two parts, at the same moment piston H in the chamber C is advancing in the direction of arrow 1, and since the two cranks are connected to the same shaft a , there is a tendency for said piston H to carry the other one, I, by the center. Herein arises the difficulty, since the valve G, co-operating with the latter piston, has completely closed the chamber, and the non-elasticity of the water prevents any change in the position of said piston therein, and consequently some of the co-operative parts must yield or break, unless, while said piston remains stationary, the crank and connecting-rod are permitted to advance.

The construction and arrangement of the pistons loosely upon their connecting-rods obviates this, and the moment the valve G has closed the passages $h h'$ the piston I stops, while the rod c advances slightly at the criti-

cal moment. The crank f' , to which it is attached, has then reached its extreme stroke and now begins to retreat. Immediately there-upon the valve has moved sufficiently to open its ports, and supply-liquid now commences to enter between the head of the meter and the piston. This flow of water with its attendant pressure then moves the piston back again until the latter abuts against the end of the connecting-rod. Thus, when said piston reaches a similar position to that above described at the opposite end of the stroke, the rod is again free to advance the slight distance required beyond where the piston stops in order to pass the center, and thus prevents any pressure being brought against said piston which would wrench, distort, or perhaps break some one of the operative parts.

I do not desire to be limited to the precise construction herein shown, since there are many mechanical expedients which may be resorted to in order to accomplish the same result. One very simple equivalent would be to make the piston fast to the connecting-rod while the latter is capable of slip upon the crank.

Now, to sum up, I consider the gist of my invention consists in the compensating slip movement between the crank and piston, whereby the latter may remain stationary for a short interval of time, while its valve has closed both ports, and the crank in reaching its center is free to move its proper distance without affecting the position of the piston.

What I desire to claim and secure by Letters Patent of the United States is—

1. In a crank water-meter, a piston loosely secured to the connecting-rod, whereby the latter and its operating-crank are permitted to move onward while the piston remains at rest just prior to the completion of a stroke, substantially as and for the purpose stated.

2. The combination, with a rotary shaft provided with a crank and its connecting-rod, of a reciprocating piston loosely attached to the extremity of the latter, whereby at certain stated times the crank and rod may move while the piston remains stationary, substantially as stated.

In testimony whereof I affix my signature in presence of two witnesses.

GEORGE HENRY FOX.
